UNITED STATES PATENT OFFICE.

STEPHEN G. STURGES, OF NEWARK, NEW JERSEY.

DESIGN FOR BUCKLES.

Specification forming part of Design No. 7,159, dated May 26, 1874; application filed February 24, 1874.
[Term of Patent 7 years.]

To all whom it may concern:

Be it known that I, STEPHEN G. STURGES, of Newark, in the county of Essex and State of New Jersey, have invented a new and original Design for Buckles, of which the following is a specification:

Figure 1 represents a perspective view of my new buckle, and Fig. 2 is an edge view of the same.

Similar letters of reference indicate corresponding parts in both the figures.

The invention relates to a new ornamental design for harness and other buckles. It con-

sists in forming the buckle with straight-connecting and ogee-curved parts.

A represents the buckle. *a a* are the sides thereof. B is the tongue. The sides and tongue are curved in opposite directions.

I claim—

The design for a buckle having straight-connecting and ogee-curved parts, as shown in the drawings.

STEPHEN G. STURGES.
